WARREN E. HUDELSON, OF SAN JOSE, CALIFORNIA.

REGULATING MEANS.

1,281,011.

Specification of Letters Patent.

Patented Oct. 8, 1918.

Application filed February 5, 1917. Serial No. 146,772.

To all whom it may concern:

Be it known that I, WARREN E. HUDELSON, a citizen of the United States, residing at San Jose, in the county of Santa Clara 5 and State of California, have invented certain new and useful Improvements in Regulating Means, of which the following is a specification.

This invention relates to regulating means, 10 and more particularly to means for regulating the water and steam pressure of a steam boiler.

One of the main objects of the invention is to provide regulating means of simple 15 construction and operation which may be applied to a boiler of standard construction for automatically regulating the water level within the boiler.

A further object is to provide means for 20 controlling the supply of fuel to the boiler in accordance with the steam pressure of the boiler, thus providing simple and efficient controlling means for regulating the pressure of the steam.

25 Further objects will appear from the detail description.

In the drawings:

Figure 1 is a vertical longitudinal sectional view through a conventional form 30 of boiler with the regulating device applied,

Fig. 2 is a central vertical sectional view taken through the water regulating device, and

Fig. 3 is a similar view taken through the 35 fuel supply regulating means.

The boiler 1 is provided with the front plate 2 spaced from the head 3 and the back plate 4. A bottom plate 5 is secured to the front and back plates, above the bottom 6 40 of the boiler, and extends to the rear head 7 of the boiler. A plurality of spaced fire-tubes 8 are suspended in the plates 2 and 4, and communicate with the smoke-box 9 at the front of the boiler between the head 3 and plate 2 and the smokestack 10 at the rear of the boiler between the head 7 and plate 4. A fuel supply nozzle 11 extends into the fire-box between the plate 5 and bottom 6 of the boiler. This nozzle 45 communicates at its outer end with a cylindrical valve-casing 12 in which is slidably mounted a cylindrical head 13 on which rests the lower end of a piston rod 14 carried by a piston 15 operative in a cylinder 16. This 50 cylinder communicates at its upper end with the top of the water space of the boiler by

means of a pipe 17. By this means the steam which is generated in the boiler and accumulates in the upper portion thereof has direct access to the cylinder 16 above 60 piston 15 so as to exert pressure on the upper surface thereof for the purpose of operating the piston. An expansion coil-spring 18 is mounted about piston rod 14 and is confined between the piston 15 and a 65 collar 19 threaded on the upper portion of casing 12. This spring acts to normally hold the piston 15 raised and to maintain the head 13 in operative position. The head 13 is provided with an upper diametrically 70 extending bore 13^a and a lower bore 13^b. When the head is in operative position, bore 13^a is in register with an oil supply-pipe 20, which is connected to a tank or other suitable source of supply of fuel oil, and 75 the bore 13^b is in register with a pipe 21 connected to a suitable source of supply of pressure fluid, this fluid being taken from a tank or directly from the steam-chamber of the boiler 1, as desired. When the head 80 is in operative position, the fuel is projected into the fire-box where it is ignited in the usual manner, the products of combustion flowing beneath the water-chamber and through the fire-tubes to the smokestack. 85 When the steam pressure in the boiler rises above a predetermined amount, the pressure exerted on the upper face of piston 15 will overcome the upward pressure of expansion-spring 18 so as to force the piston down- 90 ward in cylinder 16. The downward movement of piston 15 moves the head 13 downward into the lower portion of casing 12, so as to bring the bores 13^a and 13^b out of register with the pipes 20 and 21, thus shutting 95 off the supply of fuel, either partially or completely, to the nozzle 11. By this means the heat generated within the boiler is automatically reduced so as to reduce the amount of steam generated, and consequently the 100 steam pressure within the boiler. When the steam within the boiler has been reduced to the desired predetermined pressure, the piston 15 is returned to its initial position by the action of expansion spring 18, thus permitting the full amount of fuel to be supplied to the nozzle so that the normal quantity of steam will be generated. Normally, the fuel supply will not be completely cut off, so that the fire within the boiler will 110 not be entirely extinguished. However, if desired, a suitable igniting means, such as

a pilot light may be provided within the fire-chamber so as to insure that, when the supply of fuel is renewed, it will be properly ignited. This is not deemed necessary, however, under ordinary conditions.

10 A cylinder 22 is mounted in front of the boiler and is connected by a pipe 23 to the water-chamber, the outer end of this pipe being connected to the cylinder adjacent the lower end thereof. A hollow cylindrical float 24, which is closed at its lower end, is mounted within cylinder 22. A rod 25 is secured to the upper end of this float, at the center thereof. This rod extends through 15 a depending cylindrical packing-casing 26 at the top of cylinder 22, which is interiorly threaded to receive a packing-nut 27. A small cylinder 28 is secured on top of cylinder 22 and is provided, at the center 20 of the top with a depending interiorly threaded sleeve 29. This sleeve receives an exteriorly threaded sleeve 30. The rod 25 extends upward through sleeve 30 and is provided on its upper end, with a cylindrical valve 31 secured thereto. This valve is 25 slidably operative in the valve-casing 32. A water supply pipe 33 is connected to the pump for supplying water to the boiler under pressure and communicates with one 30 side of the valve-casing 32, and a pipe 34 communicates with the other side of the casing in axial alinement therewith, and with the water-chamber of the boiler. The valve 31 is provided with a diametrically 35 extending bore 35. When the valve is lowered this bore registers with the bores of the pipes 33 and 34, so as to permit water to be supplied to the boiler.

40 Normally, the float 24 is held in depressed position by means of an expansion spring 36 which is mounted about the rod 25 and is confined between a collar 37 secured on the rod and the lower end of sleeve 30. By 45 means of sleeve 30 the amount of compression of spring 36 may be varied so as to adjust the expansive force of the spring to suit circumstances. As the water from the boiler flows into the cylinder 22, it raises the float 24, against the action of the expansion-spring 36. This will raise the valve 31 50 into the casing 32 so as to close communication between pipes 33 and 34 and shut off the supply of water to the boiler. By adjusting the spring 36, the valve 31 may be 55 caused to operate in such manner as to maintain the water at any desired constant level within the boiler.

60 The head or valve 13 is held raised so as to bear against the rounded lower end of rod 14 by means of a coil expansion spring 41. This spring is confined between the valve and a disk 42 slidable in casing 12. An adjusting screw 43 is threaded through 65 the lower end of the casing, at the center thereof, and engages the disk. By this means

the compression of spring 41 may be varied to suit circumstances.

To prevent rotary movement of the fuel supply control valve or head 13, a set screw 38 is threaded through casing 12 and engages into a groove 39 in the head. Diametrically opposite to, and above set screw 38, a second set screw 40 is threaded through casing 12 so as to extend into the same. This set screw 40 is so positioned as to engage the upper end of head 13 so as to positively limit upward movement thereof when the head is raised into its highest position. By this means I insure that, when the pressure in the boiler has fallen to the predetermined minimum, the valve 13 will be in such position as to supply the maximum amount of fuel to the furnace. This will be true even though the pressure in the boiler falls below the predetermined minimum and the piston 15 is raised higher than the position shown in Fig. 3 of the drawings, due to the fact that valve 13 is separate from piston-rod 14.

To permit adjustment of spring 18, the lower portion of cylinder 16 is provided with a plurality of spaced longitudinal slots, as in Figs. 1 and 3 of the drawings. This permits ready access to the adjusting collar 19 whereby it may be quickly and easily adjusted on casing 12 thus varying the compression of spring 18. As will be noted, these slots are of such length as to avoid interference with the proper operation of piston 15.

The valve 31 for controlling the water supply is secured against rotary movement by a set screw 44 which engages into a longitudinally extending groove in the head. This insures that bore 35 of the valve will 105 be brought into proper register with the pipes 33 and 34 when the valve is in its lowest position.

110 By providing a boiler with feed water regulating means and steam pressure regulating means, such as shown and described, an automatic control of the boiler is established which acts to insure that the steam pressure and the water level will be maintained at the desired predetermined level 115 or pressure. It will be evident that the regulating means shown and described may be equally well applied to any boiler of any standard construction other than that disclosed herein. Of course, in applying my 120 regulating means to different types of boilers there may be slight changes made in the construction and arrangement of the various parts of the invention, which will fall within the field and scope of the claim and it is 125 intended to include all such variations in this application, in which the preferred form only of my invention is disclosed.

What I claim is:

130 The combination with a boiler having a

fire chamber, of a fuel supply nozzle communicating with said chamber, a cylinder communicating at its upper end with the steam space of said boiler, the lower portion of said cylinder being provided with a plurality of radially disposed longitudinally extending slots, a valve casing secured in the lower end of the cylinder, the upper portion of said casing projecting into said cylinder, an adjusting nut threaded on the upper portion of the valve casing within the cylinder, a valve operative in said casing and interposed between said fuel nozzle and supply pipe so as to control the flow of fuel to said nozzle, said valve having limited upward movement, a depending rod carried by said piston, the lower end of said rod resting upon the upper face of the valve, a coil expansion spring mounted about said piston rod and confined between the piston and said adjusting nut, and adjustable means for forcing said valve upwardly in its casing.

5 20

In testimony whereof I affix my signature in presence of two witnesses.
